UNITED STATES PATENT OFFICE

STANLEY A. LIBOLD, OF DULUTH, MINNESOTA

DESIGN FOR A CANDLESTICK OR ARTICLE OF ANALOGOUS NATURE

Application filed May 14, 1931. Serial No. 39,848. Term of patent 14 years.

To all whom it may concern:

Be it known that I, STANLEY A. LIBOLD, a citizen of the United States, and resident of Duluth, in the county of St. Louis and State of Minnesota, have invented a new, original, and ornamental Design for Candlesticks or Article of Analogous Nature, of which the following is a specification, reference being had to the accompanying drawings, forming part thereof, in which,—

Claim:

The ornamental design for a candlestick or article of analogous nature substantially as shown.

Dated, May 8th, 1931.
